CLAIM

The ornamental design for a toothbrush holder, as shown and described.

DESCRIPTION

FIG. 1 is a side view of a toothbrush holder incorporating my new design with all side views being a mirror image thereof;

FIG. 2 is a top view of the toothbrush holder of FIG. 1;
FIG. 3 is a bottom view of the toothbrush holder of FIG. 1;

FIG. 4 is a cross-sectional view taken along the line and viewed in the direction of arrows 4—4 of FIG. 2;

FIG. 5 is a top view of FIG. 1 with the lid removed;
FIG. 6 is a side view of the removed lid of FIG. 1; and,
FIG. 7 is a bottom view of the lid of FIG. 6.
